UNITED STATES PATENT OFFICE

KRISTIAN NICOLAUS WANNEBO, OF GOTTERBURG, SWEDEN

PROCESS OF MAKING OIL GAS

Application filed March 26, 1926, Serial No. 97,743, and in Germany September 11, 1923.

The object of this invention is to produce gas from oil or tar in a generator, obtaining aromatic or gasoline-like products as a by-product.

One form of generator for carrying out this process is shown in the accompanying drawing which is a vertical sectional view of the oil gas generator. The generator consists of two identical, vertical and cylindrical steel shells, A and B connected at the top by the conduit 1. The shells A and B are closed at both ends with steel end plates. If the gas making is to be conducted at a relatively high pressure, the end plates should preferably be of a spherical form. The generators are lined with firebrick or other refractory material. The shells A and B are divided into compartments by two or more arches in each shell. The arches are of firebrick or other refractory material. The arches are perforated. Above the arches are checkerworks of firebrick or other refractory material to act as reservoirs of heat.

At the tops of A and B are located one or more atomizers 5 and 5' for injecting pre-heated oil or tar used in this process. At 2 and 2' are inlets for air and fuel, which may be liquid or gaseous, for heating up the generator before starting the process. At the bottom of A and B are located inlets 3 and 3' for the introduction of the air required for combustion during the oil gas making process. The outlets 4 and 4' are connected to the stack which is not shown on the drawing. Gas offtakes 7 and 7' are connected by valves 8 and 8' and a common conduit 10 to the tar pot 11 and heat exchanger 9. The heat exchanger acts to preheat the oil or tar that is to be treated. The oil gas enters the heat exchanger through inlet 12 and passes out through valve 13 to coolers, scrubbers and other devices (not shown) known in the art of gas production for removing condensable vapors and purifying the gas prior to its distribution. 14 is a valve connecting with the stack (not shown). The oil to be treated enters the heat exchanger through inlet 15 and leaves through outlet 16. 17, 18 and 19 are outlets from the tar pot and heat exchanger for tar and oil that has condensed out of the

gas. Inlets 6 and 6' are for the admission of steam for expelling unconsumed air from this part of the apparatus prior to changing the operation cycle.

The operation of the process will be best understood by referring to the above description and to the drawing. The generator if cold, is first heated by introduction of air and fuel via 2. The products of combustion rise in A, pass through pipe 1, then pass through B and out via 4' to the stack. The arches, checkerwork and lining are heated. During the operation, the inlets 3 and 3', for admission of air, inlets 6 and 6' for admission of steam and connection 4 to the stack are all closed. After the heating has been carried out for some time in this direction, it is stopped. The direction of the heating gases are reversed by introducing air and fuel via 2'. The hot gases then pass in an opposite direction and out through 4. The heating of the generator is thus carried out alternately via 2 and 2' until the desired temperature has been obtained. This temperature may be recorded by pyrometers located in the generator. Instead of passing the combustion gases via 4 and 4' to the stack, they may be led via valves 8 and 8' through the heat exchanger 9 and thence through a valve 14 to the stack. When the heating is completed, air and fuel inlets may be removed from 2 and 2' and the ports filled with fireproof material. The openings in the shells A and B may be covered with suitable dummy flanges. This operation is to prevent the coking up of the heating apparatus which is no longer required and to prevent any leakage at this point.

The generator is now ready for the oil gas making process. Oil or tar is injected via 5 and 5' with gas offtakes 7 and 7' open and all other valves closed. The oil or tar will be gasified by the heat in the generator. The products will pass down through A and B and out through the gas offtakes to the tar pot and heat exchanger. In passing through the generator the gases deposit free carbon formed in the gasification process. The major portion of this carbon is deposited in the upper hotter portion of the generator.

After the generator has thus reached a normal working condition with carbon and lamp black deposited on this hotter part of the generator, the valve in the gas offtake from A, i. e., valve 8, is closed and air for combustion is admitted through the air inlet 3. The air rises through the arches and checkerworks in A and is heated by the same. The preheated air on reaching the glowing carbon which has been deposited in A, burns it mainly to carbon monoxide, developing the heat necessary for the heating and gasification of the tar or oil and also sufficient heat to make up heat losses from the generator.

The mixture of products of combustion oil gas, and oil and tar vapors, pass down through B and pass out through 7', tar pot 11, and heat exchanger 9. On the way through B the vapors and gases deposit free carbon and heat the lower or cooler part of B and are themselves cooled. After the gas making has been carried out thus for some time, the air inlet 3 is closed steam is then introduced for a short time through 6 in order to expel unconsumed air in A. The steam is superheated in its passage through A. When it comes in contact with the glowing carbon in A and B, water gas is produced if all carbon in A has not been earlier consumed.

This water gas passes out of the generator and through the outlet 7' together with the other gases. The steam inlet 6 is then closed, the valve 8 is opened and the valve 8' closed. The air inlet 3' is then opened. The gas making is carried on but in the opposite direction.

In this manner gasification proceeds in alternate directions, practically continuously, with but small variations in the quality of the vapors and gases produced.

Oil or tar is introduced the whole time, but the amount of oil or tar introduced through the different atomizers is altered according to the cycle of the process. At the end of each period, when most of the carbon deposited on the checkerwork in the shell, into which air is introduced, has been consumed and the combustion zone approaches the upper part of the shell, it is necessary to interrupt for a short time the introduction of oil or tar through the atomizers located at the top of same shell, to prevent accumulation of carbon in the upper part of the generator.

The average temperature of the generator is regulated by varying the relative proportions of the oil or tar and the air for combustion which is introduced and partly by varying the quantity of steam used. As the quantity of air introduced is increased the temperature rises. The temperature falls as the quantity of air is diminished. As the temperature is increased, the amount of deposited carbon increases and the quantity of by-products in the gases decreases. The character of the by-products is also altered.

At relatively low gasification temperatures, the tar which condenses out of the gases contains a large percentage of gasoline-like hydrocarbons and only a small percentage of aromatic hydrocarbons. As the gasification temperature increases the amount of light hydrocarbons in the condensate decreases. These are mainly of the aromatic series. At still higher temperatures these are decomposed, the tar decreases in quantity and is of higher specific gravity.

Time is also a very important factor. At a given temperature the decomposition of the hydrocarbons is carried further during slow gasification than during faster gasification at the same temperature. If in the same generator, at the same temperature, the same amount of the same oil per unit of time is treated, first at a low pressure and then at a higher pressure, in the second instance the decomposition will be carried further. This because the products, being more compressed, will take a longer time in passing through the generator. Pressure has an additional effect on the process of decomposition. At higher pressures, all other factors being the same, the condensable hydrocarbons produced will contain a relatively higher percentage of saturated hydrocarbons than if the process had been carried out at a lower pressure.

If the gas making is carried out at so low a temperature that the amount of carbon deposited is less than is required to generate the heat necessary for the process, a part of the injected oil or the gas derived from the oil is burned. If more carbon is deposited than is necessary to develop the heat necessary for carrying out the process and thus tends to accumulate in the generator, the amount of air is increased and a corresponding amount of steam injected. The excess carbon is burned producing producer gas without increasing the temperature. If it thus is not desired to dilute the gas made in the process with producer gas, the process must be interrupted from time to time and the carbon removed by blowing air and steam through the generator.

This method of manufacturing gas from oil or tar, renders it possible to produce a cheap gas from cheap oil, fuel oils, tars and such like, with a minimum fuel consumption. According to this method, not only the oil used for producing gas, but also the air for combustion is preheated. The quantity of combustion products produced in the generation for the heat necessary for the process, is so small, that the gas mixture obtained may have a fuel value of 550 British thermal units per cubic foot or even more.

At the same time it is possible to so control the process, as to allow large quantities of valuable by-products to be obtained. On account of the fact that the oil gas is diluted

with the products of combustion it is, it is true, more difficult to remove the condensable hydrocarbons from the gas, but as the process is continuous, although the direction reverses, 5 it is possible to carry on the gasmaking and consequent cooling and scrubbing of the gas at a higher pressure, and remove the condensable hydrocarbons in the manner employed in the art of manufacturing gasoline 10 from natural gas.

The generator for producing gas according to this method, can of course be constructed in different ways, and the invention is not confined to the form shown but modifications may be made within the scope of the 15 claims.

Having now particularly described and ascertained the nature of my invention, I declare that what I claim is:

20 1. A process of making oil gas in a two-shell checkerbrick oil gas generator; which comprises heating the checkerbrick in the shells, introducing oil continuously at an intermediate point between the heated checkerbrick in the two shells, simultaneously introducing air below the checkerbrick in one of the shells and passing the generated oil gas from the lower portion of the other shell, then shutting off the air from the first-mentioned shell and simultaneously admitting air below the checkerbrick of the second-mentioned shell whereby the generated oil gas passes from the lower portion of the first-mentioned shell, and periodically reversing 30 the course of the air and generated oil-gas.

25 2. A process of making oil-gas in an oil-gas generating apparatus containing heated checkerbrick, which process consists in introducing oil continuously at an intermediate 35 point, simultaneously introducing air at one end of the generator and passing the generated oil-gas from the other end of the generator, then shutting off the air from the first-mentioned end of the generator and simultaneously admitting air at the other end of the generator and passing the generated oil-gas from the first-mentioned end of the generator, and periodically reversing the course of the air and generated oil-gas.

40 3. In witness whereof, I have hereunto signed my name.

KRISTIAN NICOLAUS WANNEBO.
